UNITED STATES PATENT OFFICE.

WILLIAM REDFORD MULOCK, OF WINNIPEG, MANITOBA, CANADA.

PLATEN FOR TYPE-WRITING MACHINES.

1,244,759.

Specification of Letters Patent. Patented Oct. 30, 1917.

Application filed May 14, 1917. Serial No. 168,433.

To all whom it may concern:

Be it known that I, WILLIAM REDFORD MULOCK, a subject of the King of Great Britain, residing at Winnipeg, in the Province of Manitoba, Canada, have invented certain new and Useful Improvements in Platens for Type-Writing Machines, of which the following is a full, clear, and exact specification.

10 This invention relates to platens for type-writing machines and has for its object to reduce to a minimum the noise incident to the type striking the platens.

To eliminate the noise, each platen should 15 consist of a tubular layer of elastic cushioning substance supported upon a sound deadening core, and in order to produce clear impressions of the type upon the paper, it is necessary that said cushioning layer be provided with a hard covering. The hard covering is made relatively thin and divided 20 into small parts in order to obtain the maximum resiliency without impairing the clearness of the impressions. The core consists 25 of a thin metal cylinder filled with a sound deadening substance. This cylinder is made as thin as possible and in the form of lattice work, the interstices being of the largest size possible without destroying the smooth 30 exterior surface of the cushioning tube, so that said cylinder contains the least quantity of metal necessary to give it rigidity.

The invention will be first hereinafter described in connection with the accompanying 35 drawings which constitute part of this specification, and then more specifically defined in the claims at the end of the description.

In the accompanying drawings, wherein 40 similar reference characters are used to designate corresponding parts in both views:

Figure 1 is a broken side view of a typewriter platen made substantially in accordance with this invention, the wire constituting 45 the outer covering of the platen being shown on an enlarged scale for the sake of clearness, and

Fig. 2 is a transverse section of the platen.

In the drawings, 1 designates the metal 50 cylinder for supporting the tubular layer of elastic cushioning substance 2. The cushioning substance used is soft rubber, and around it is wound wire 3 forming the hard surface for the platen which is necessary in order 55 to produce clear impressions. The wire is closely coiled or otherwise arranged to form

a substantially even surface and is of fine gage so that the impact or stroke of the type will be against as small a hard surface as possible. The coils of the wire constitute 60 small parts of the hard outside casing which are adapted to move independently of one another under the impact of the type by reason of the yielding quality of the elastic cushioning layer.

65 The metal cylinder 1 is made very thin in order to reduce to a minimum the sound conducting substance thereof, and for the same reason it is made in the form of lattice work with interstices therein of any desired 70 shape and as large as possible without impairing the rigidity of the cylinder. The interstices may be round, as illustrated at 5 in solid lines, or said interstices may be in any other shape as suggested by the diamond shaped openings indicated by the dotted lines 6. At the same time the interstices of this lattice work cylinder must be small enough to prevent the tubular cushioning layer from losing its smooth exterior by being drawn or sunk into them when the wire 75 is wound upon said cushioning layer.

80 The sound deadening substance 4 may be soft wax, or any other suitable material, and is used merely as a filling so as to prevent the space within the lattice cylinder from forming a resounding chamber which would be the case if said space were left open.

85 Having thus described my invention what I claim as new and desire to secure by Letters Patent of the United States is:

90 1. A noise reducing platen for typewriters comprising in combination a tubular layer of an elastic cushioning substance, a hard outside casing surrounding the elastic cushioning layer and composed of small parts adapted to move independently of one another under the impact of the type by reason of the yielding quality of said elastic cushioning layer, a lattice work cylinder supporting 95 said elastic cushioning layer, and a filling of a sound deadening substance in said cylinder.

100 2. A noise reducing platen for typewriters comprising in combination a tubular layer of an elastic cushioning substance, a hard outside casing surrounding the elastic cushioning layer and composed of small parts adapted to move independently of one another under the impact of the type by reason of the yielding quality of said elastic cushioning layer, a metal cylinder engaging 110

the inner surface of the elastic cushioning layer and consisting of the minimum amount of metal necessary to rigidly support said elastic cushioning layer and hard outside casing, and a filling of a sound deadening substance in said cylinder.

3. A noise reducing platen for typewriters comprising in combination a layer of elastic cushioning substance, a thin outside casing 10 of hard material, a metal cylinder engaging the inner surface of the elastic cushioning layer and consisting of the minimum amount of metal necessary to rigidly support said elastic cushioning layer and hard outside 15 casing, and a filling of a sound deadening substance in said cylinder.

4. A noise reducing platen for typewriters comprising in combination a layer of an elastic cushioning substance, an outside casing 20 composed of a relatively thin layer of wire coiled about said elastic cushioning layer to form a substantially even surface, a metal cylinder engaging the inner surface of the elastic cushioning layer and consisting 25 of the minimum amount of metal necessary to rigidly support said elastic cushioning layer and hard outside casing, and a filling of a sound deadening substance in said cylinder.

30 5. A noise reducing platen for typewriters comprising in combination a layer of elastic cushioning substance, a thin metal outside casing, a thin cylinder of hard material en-

gaging the inner surface of the elastic cushioning layer for supporting the same, and 35 a filling of a sound deadening substance in said cylinder.

6. A noise reducing platen for typewriters comprising in combination a layer of elastic cushioning substance, a relatively thin outside 40 casing of hard material, a relatively thin cylinder of hard material engaging the inner surface of the elastic cushioning layer for supporting the same, and a filling of a sound deadening substance in said cylinder 45 for the purpose specified.

7. A noise reducing platen for typewriters comprising in combination a layer of elastic cushioning substance, a thin outside casing 50 of hard material, and a solid core of a sound deadening substance to support said elastic cushioning layer.

8. A noise reducing platen for typewriters comprising in combination a tubular layer 55 of an elastic cushioning substance, a hard outside casing surrounding the elastic cushioning layer and composed of small parts adapted to move independently of one another under the impact of the type by reason of the yielding quality of said elastic 60 cushioning layer, and a solid core of a sound deadening substance to support said elastic cushioning layer.

In testimony whereof I have signed my name to this specification.

WILLIAM REDFORD MULOCK.
